UNITED STATES PATENT OFFICE.

ALEXANDER VAUGHAN, OF CHICAGO, ILLINOIS, ASSIGNOR TO THE VAUGHAN & BUSHNELL MANUFACTURING COMPANY, OF SAME PLACE.

DESIGN FOR A WRENCH-HANDLE.

SPECIFICATION forming part of Design No. 29,767, dated December 6, 1898.

Application filed September 8, 1898. Serial No. 690,534. Term of patent 14 years.

To all whom it may concern:

Be it known that I, ALEXANDER VAUGHAN, a citizen of the United States, residing at Chicago, Cook county, Illinois, have invented and produced a new and original Design for a Wrench-Handle, of which the following is a specification.

In the accompanying drawings, Figure 1 is a side elevation of a wrench-handle presenting my design; Fig. 2, a side elevation, partly in section; and Fig. 3, an edge view of the handle.

In the drawings, A is a wrench-handle; B, the enlarged end thereof, integral therewith and extending longitudinally therefrom; and b, the mortise extending partially through the enlarged end from its top and rear.

The leading feature of my design consists in a wrench-handle A, having an enlarged end B integral therewith and extending longitudinally therefrom, and a mortise b extending partially through the enlarged end from its top and rear, the whole presenting an ornate and attractive appearance, as shown in the drawings. 20

I claim—

The design for a wrench - handle herein shown and described.

ALEXANDER VAUGHAN.
